UNITED STATES PATENT OFFICE.

OLIN M. ALEXANDER, OF ANNISTON, ALABAMA.

FLUSHING-TANK.

SPECIFICATION forming part of Letters Patent No. 792,955, dated June 20, 1905.

Application filed July 5, 1904. Renewed May 15, 1905. Serial No. 260,588.

To all whom it may concern:

Be it known that I, OLIN M. ALEXANDER, a citizen of the United States, residing at Anniston, in the county of Calhoun and State of Alabama, have invented new and useful Improvements in Flushing-Tanks, of which the following is a specification.

This invention relates to flushing-tanks, and aims to provide a tank of such class which shall be simple in its construction, strong, durable, efficient in its use, readily placed in and removed from its operative position, and comparatively inexpensive to manufacture.

The invention further aims to provide a flushing-tank which will overcome the usual noise made by the siphon, as well as overcome the noise generally created when refilling the tank after the flushing operation.

The invention further aims to provide a flushing-tank which can be mounted in the wall of a dwelling or inclosed in the wall of a dwelling, thereby overcoming the unsightly projecting boxes or tanks now in general use.

The invention further aims to provide a flushing-tank with means to increase or decrease the amount of water held by the tank and to further provide means for discharging the water from the tank more rapidly than the supply of the water to the tank, at the inlet part thereof.

With the foregoing and other objects in view the invention consists of the novel combination and arrangement of parts hereinafter more specifically described, illustrated in the accompanying drawings, and particularly pointed out in the claims hereunto appended.

In describing the invention in detail reference is had to the accompanying drawings, forming a part of this specification, and where like characters of reference denote corresponding parts throughout the several views, and in which—

Figure 1 is a sectional elevation of a flushing device constructed in accordance with this invention. Fig. 2 is a top plan view of the float shown in Fig. 1. Fig. 3 is an enlarged perspective view of a split screw used for closing the water-passage of the float shown in Fig. 1. Fig. 4 is a sectional elevation of a modified form of flushing device constructed

in accordance with this invention. Fig. 5 is a sectional view of the lower portion of the device illustrated in Fig. 4, showing the plunger in its elevated position. Fig. 6 is a view similar to Fig. 5, showing the various positions in full and dotted lines of the valve for closing communication between the reservoir-section and the plunger-section; and Fig. 7 is an elevation showing the plunger in both constructions.

A flushing-tank constructed in accordance with this invention comprises what may be termed two "sections," one of which is designated the "reservoir-section" and, as shown in Fig. 1 of the drawings, terminates at its bottom into what is designated the "plunger-section;" but, as shown in Fig. 4 of the drawings, the reservoir-section is detachably connected at its bottom to the plunger-section. The reservoir-section is detachably connected at its top in a manner hereinafter referred to to a water-supply, and the plunger-section is detachably connected at its bottom in a manner hereinafter referred to to the ordinary stand-pipe.

The reservoir-section consists of an oval-shaped tank or receptacle 1, adapted to receive a supply of water for flushing purposes, and said tank or receptacle 1 is contracted at its top, or, in other words, has its top formed substantially conical, with an opening at the apex thereof. The top of the tank or receptacle 1 is designated by the reference character 2, and the opening therein is designated by the reference character 3, and said top 2 is provided with a flange 4 to permit of connecting the tank or receptacle 1 through the medium of a coupling-band 5 with a water-inlet supply-pipe 6, having a cut-off 7. The reservoir-section further comprises a hollow float 8, provided with a centrally-arranged water-passage 9, which is closed at its bottom through the medium of an adjustable split screw 10, the latter regulating the flow of water out through the bottom of said passage 9. The float 8 is adapted to contain gas or air, as desired, and is of such diameter with respect to the inner diameter of said tank or receptacle 1 as to form a space or passage 11 between the inner face of the tank or receptacle 1 and the outer face 100

of said float 8, thereby permitting of the flow of water, or rather the supply of water, from the top of said tank or receptacle 1 to the lower portion thereof, causing thereby the 5 float to rise. The float 8 is provided with an extensible and removable enlarger or diminisher 12, which is in the form of a plurality of removable collars, (only one shown,) and said collars or strips are adapted to increase 10 or decrease the quantity of water supplied to the tank or receptacle 1, as well as regulate the supply thereof. When the width of the passage 11 is regulated, the flow of water through the passage 9 is also regulated by adjusting the split screw 10. It may be well to 15 state that the head 13 of the split screw 10 is adapted to close the outlet end of the passage 9. Depending from the bottom of the float 8 is a wedge-shaped deflecting-blade 14, which 20 is hinged at its upper end, as at 15, to one side of the said float 8. The function of said deflecting-blade 14 will be hereinafter referred to. As shown in Fig. 1, the lower portion of 25 the tank or receptacle 1 is contracted, as at 16, and terminates in the plunger-section, to be hereinafter referred to, and by contracting the said lower end of the tank or receptacle 1 a pocket 17 is provided for the shiftable globular valve 18, said valve 18 being constructed 30 of any suitable material. At one side of the pocket 17 an adjustable retaining-screw 19 is provided for holding the valve 18 in the pocket 17 when said valve 18 is shifted off its seat and until said valve 18 is shifted out of 35 the pocket 17 through the medium of the deflecting-blade 14 in a manner as hereinafter referred.

The plunger-section comprises a tubular portion 20, which is arranged at the upper 40 end of said plunger-section and terminates in the bottom of said reservoir-section and has the inner face at the upper end thereof beveled, as at 21, to form a valve-seat for the valve 18. The tubular section 20 extends into 45 a casing 22 and has one portion secured to said casing, as at 23, and the other portion terminating into a forwardly-projecting apertured guide-arm 24. The casing 22 projects rearwardly, as at 25, and then upwardly 50 at the back of said tubular portion 40, as at 26, and forms a passage 27, the function of which will be hereinafter referred to. The rearwardly-extending portion 25 of the casing 22 is arranged at a point removed from the 55 arm 24, thereby forming a chamber 28, the function of which will be hereinafter referred to. The lower end of the casing 22 is connected to the ordinary stand-pipe through the medium of a coupling-collar 29. Vertically 60 operable within the tubular portion 20 is a hollow plunger 30. Said plunger is open at its top, closed at its bottom, and open at its front, at the lower end thereof, as indicated by the reference character 31. The upper 65 face of the closed bottom of the plunger is

formed in a curvilinear manner, (indicated by the reference character 32,) and secured to the upper end of the plunger 30, as well as projecting across the upper open end of the said plunger 30, is an upwardly-extending inclined 70 knife-shaped shifting-arm 33. Said arm is adapted to shift the valve 18 off its seat and into the pocket 17 when the plunger 30 is moved upwardly. Secured to and depending from the bottom of the plunger 30 is a short arm 34, 75 which at its lower end is connected to the L-shaped operating-rod 35 for the plunger, the arm 34 and the lower portion of the rod 35 being arranged within the chamber 28, and the vertically-extending part of said rod 35 80 is adapted to operate in the passage 27. The upper end of the rod 35 is connected to the inner end of an operating-lever 36, as at 37, and said lever 36 carries a handle 38 and has its fulcrum in a bracket 39, secured to the 85 outer face of the tank or receptacle 1.

The operation of the structure, as shown in Fig. 1, is as follows: It will be assumed that the tank or receptacle 1 is filled with water and that the float 8 is at the top thereof. The 90 handle 38 is grasped and the lever 36 rocked on its fulcrum, which will impart a vertical movement to the rod 35, elevating the plunger 30 upwardly within the tubular portion 20, bringing the shifting-arm 33 against the 95 valve 18, and shifting the valve 18 over into the pocket 17. When the valve 18 is shifted on its seat, the water will be exhausted from the tank. When the lever 36 is released, the plunger 30 will assume its normal position, 100 which is resting upon the arm 24. As the water discharges from the tank or receptacle 1 the same will pass through the hollow plunger into the casing 22 and thence into the stand-pipe. As the water is being exhausted 105 from the tank the float 8 will be lowered and which will eventually cause the deflecting-blade 14 to engage the valve 18 and move it from the pocket 17 back and upon its seat 21, consequently preventing the discharge of any 110 more water from the tank or receptacle 1 and permitting of the tank being again supplied with water, and as the water is being supplied to the tank or receptacle 1 the float will 115 gradually rise therein.

The float 8 is substantially of the same contour as the tank or receptacle 1, and when desired suitable means may be employed for guiding the float 8, and also the necessary packing can be employed for the short arm 120 34 as well as the rod 35.

In the modified construction (shown in Figs. 4, 5, and 6) a detachable reservoir-section and a detachable plunger-section is employed, and said reservoir-section consists of an oval-shaped tank or receptacle 37, which is contracted at its top and provided with an upwardly-extending tubular extension 38, adapted to be connected, through the medium of the coupling-band 39, to a water-inlet supply-pipe 130

40, having a cut-off 41. The reservoir-section further comprises a hollow float 42, which is closed at its bottom and top and which may carry air or gas and is of such diameter with 5 respect to the inner diameter of the said tank or receptacle 37 as to form a space or passage 43 entirely around said float 42 to permit of the flow of water, or rather the supply of water, from the top of said tank or receptacle 10 37 to the lower portion thereof, causing thereby the float 42 to rise. The float 42 is provided with an extensible and removable enlarger or diminisher 44 in the form of a plurality of collars, (only one shown,) and said 15 collars or strips are adapted to increase or decrease the width of the passage 43, thereby increasing or decreasing the quantity of water supplied to the tank 37 or for regulating the supply of water to the tank or receptacle 20 37. Depending from the bottom of the float 42, at one side thereof, is a wedge-shaped deflecting-blade 45, which at its upper end is hinged to said float 42, as at 46. The function of the said deflecting-blade 45 is the same 25 as the deflecting-blade 14. (Shown in Fig. 1.) The lower portion of the tank or receptacle 37 is contracted, as at 47, and is further formed with a vertically-extending tubular extension 48, which is secured, through the medium of 30 the coupling-collar 49, to the plunger-section, which will be hereinafter referred to. The contracted portion 47 of the tank or receptacle 37 forms a pocket 50 for a shiftable globular valve 51, said valve being constructed of any suitable material. At one side of 35 the pocket 47 a protuberance 52 is provided for retaining the valve 51 within the pocket 50 when said valve 51 is shifted off its seat. At the top of the tubular portion 48 a valve-seat 53 is provided for the valve 51, and for 40 this purpose the inner face of said tubular portion 48 at its upper end is beveled. Above the valve-seat 53 the inner face of the rear wall of the tank or receptacle 37 is formed 45 with a beveled guide offset 54 to assist in deflecting the valve 51 when the latter is shifted off its seat into the pocket 50. The plunger-section comprises a casing formed with an elbow-shaped portion 55, terminating at its 50 top in a vertically-extending tubular portion 56, which is connected to the tubular portion 48 of the reservoir-section through the medium of the coupling-collar 49. The tubular portion 56 at its bottom is formed with an opening 57, 55 the function of which will be hereinafter referred to, and the elbow-shaped portion 55 is provided with an opening 58 and further provided with a rearward extension 59, forming substantially what may be termed a "drip- 60 cup" for receiving the water that may pass through the opening 57, which after dropping into the rearward extension 59 passes into the elbow-shaped portion 55 through the opening 58. The lower end of the elbow-shaped portion 55 is connected with the ordinary stand-

pipe through the medium of the coupling-collar 60. Operating within the tubular portion 56 is a hollow plunger 61 of substantially the same construction as the hollow plunger shown in Fig. 1, and said plunger 61 at its top is 70 formed with a shiftable arm 62 of the same construction as that shown in Fig. 1. The lower end of the plunger 61 has connected thereto an operating-rod 63, said rod operating through the opening 57 and is connected 75 at its lower end to the inner end of an operating-lever 64, which finds its fulcrum in a bracket 65, carried by the elbow-shaped portion 55. The operating-lever 64 is provided with a handle 66. The operation of the device shown in Figs. 4, 5, and 6 is the same as that hereinbefore referred to in connection with the device shown in Fig. 1.

The tank or receptacle 1 or 37 is provided with any suitable means to permit of having 85 access thereto when occasion requires. The tank or receptacle 1 or 37 may be constructed of any suitable material and of any other shape than that as shown, the structure shown being the preferred contour. The operating-levers 36 or 64 may, if desired, be connected with the closet-seat in such manner as to operate automatically and also be provided with the handles, as shown, so as to be operated 90 manually.

By providing the means for increasing the width of the passage 11 or 43 the device can flush double or triple the amount of water it holds when not flushed or when inactive. The device being preferably rounded or oval and at the same time comparatively small, the tank or receptacle can therefore be made ornamental and sightly. The same may be constructed of brass or white enamel in conformity to the other parts of the bath-room fixtures, or, if desired, the device can be entirely hidden out of sight—that is to say, built within the wall of the building. The space around the float, as before stated, can be regulated so as to increase or decrease it, as desired, so that 100 twice or thrice the amount of water held by the tank or receptacle will be flushed, since water will flow into the inlet while it is flowing out at the outlet; but owing to the size of the outlet with respect to the inlet the water 105 will flow out at the outlet faster than it will flow into the inlet, thus lowering the float, and by such construction it enables one to diminish the size of the tank or receptacle for 110 containing water.

It is thought the many advantages of a flushing device constructed in accordance with the foregoing description, taken in connection with the accompanying drawings, can be thoroughly understood, and it will furthermore be 115 evident that changes, variations, and modifications can be resorted to without departing from the spirit of the invention or sacrificing any of its advantages, and I therefore do not wish to restrict myself to the details of con- 120 125 130

struction hereinbefore described and as shown in the accompanying drawings, but reserve the right to make such changes, variations, and modifications as come properly within the 5 scope of the protection prayed.

Having thus fully described my invention, what I claim as new, and desire to secure by Letters Patent, is—

1. A flushing device comprising a reservoir-section and a plunger-section communicating therewith, a valve arranged within said reservoir-section for normally closing the communication between the two sections, means operable within said plunger-section for shifting said valve from its normal position, thereby opening communication between the two sections, and a float operable in said reservoir-section and provided with means adapted to engage said valve for moving said valve to its normal position, thereby closing the communication between the said sections.
2. A flushing device involving a reservoir-section having an inlet and an outlet, a shiftable valve for closing said outlet, and a float 25 operable in said section and provided with means adapted to engage directly with said valve for moving it to its closure position after the same has been shifted, combined with means for shifting said valve.
3. A flushing device involving a reservoir-section having an inlet and an outlet, a shiftable valve for closing said outlet, and a float operable in said section and provided with means adapted to engage directly with said 35 valve for moving it to its closure position after the same has been shifted, combined with a vertically - operable and gravity - return means for shifting said valve from its closure position.
4. A flushing device involving a reservoir-section having an inlet and an outlet, a shiftable valve for closing said outlet, and means operable in said section for returning said valve to its closure position after being shifted, 45 combined with a plunger-section adapted to communicate with said reservoir-section when said valve is shifted from its closure position, said plunger-section provided with a vertically-operable and gravity-return hollow plunger provided with an inclined shifting-arm adapted to engage said valve when said plunger is operated, thereby shifting said valve from its closure position.
5. A flushing device comprising a reservoir-section and a plunger-section adapted to communicate therewith, said reservoir-section having an inlet and an outlet, a shiftable valve for closing said outlet, and a float provided 55 with means adapted to engage said valve for returning it to its normal position after being shifted, and said plunger-section provided with a vertically-operable and gravity-return plunger adapted when operated to engage said valve for shifting it from its closure position.
6. A flushing device comprising a reservoir-

section and a plunger-section adapted to communicate therewith, said reservoir-section having an inlet and an outlet, a shiftable valve for closing said outlet, and a float provided with means adapted to engage said valve for 70 returning it to its normal position after being shifted, and said plunger - section provided with a vertically-operable and gravity-return hollow plunger having a shifting-arm adapted to engage said valve when said plunger is 75 operated, thereby shifting said valve from its closure position.

7. A flushing device comprising a reservoir-section and a plunger-section adapted to communicate with each other, said reservoir-section provided with a globular valve for closing communication between the two sections, and said plunger-section provided with a vertically-operable and gravity - return hollow plunger having an inclined shifting - arm 85 adapted when said plunger is operated to engage said valve and shift the same, thereby opening communication between the two sections.

8. A flushing device comprising a reservoir 90 and a plunger section adapted to communicate with each other, said reservoir having an inlet and an outlet and a valve for normally closing said outlet, said reservoir-section further provided with a pocket adapted to receive said 95 valve when shifted and further provided with means for retaining the valve within the pocket, said reservoir-section further provided with a float having means adapted to engage said valve for moving said valve out of said 100 pocket, thereby returning the valve to its normal position, and said plunger-section provided with a vertically-operable and gravity-return hollow plunger adapted to engage the said valve for shifting it from its seat, there- 105 by opening said outlet.

9. A flushing device comprising a reservoir and a plunger section adapted to communicate with each other, said reservoir-section having an inlet and an outlet and a valve for normally 110 closing said outlet, said reservoir-section further provided with a pocket adapted to receive said valve when shifted and further provided with means for retaining the valve within the pocket, said reservoir-section fur- 115 ther provided with a float having means adapted to engage said valve for moving said valve out of said pocket, thereby returning the valve to its normal position, and said plunger-section provided with a vertically - operable 120 and gravity-return plunger adapted to engage said valve for shifting it, thereby opening said outlet.

10. A flushing device involving a reservoir-section comprising a tank, and a float operable in said tank and of such diameter as to form a passage between it and the tank, said float provided with means for increasing or decreasing the width of said passage.

11. A flushing device involving a reservoir- 130

section comprising a tank, a float operable in said tank and of such diameter as to form a passage between it and the tank, said float provided with means for increasing or decreasing the width of said passage, said float further provided with a centrally-arranged passage, and adjustable means for closing the lower end of said centrally-arranged passage.

5 12. A flushing device comprising a reservoir and a plunger section adapted to communicate with each other, a shiftable valve for normally closing communication between said sections, a vertically-movable means arranged within said reservoir-section and when moving in one direction adapted to directly engage said valve for shifting it to normal position, and means arranged in said plunger-section and adapted when operated to engage said valve and shift it from normal position.

10 13. A flushing device comprising a reservoir and a plunger section adapted to communicate with each other, a shiftable globular valve for closing communication between the two sections, said reservoir-section provided with a pocket adapted to receive said valve when shifted from normal position, means arranged in said plunger-section and adapted when operated to engage said valve for shifting it into said pocket, and a vertically-movable means arranged in said reservoir-section and adapted to engage said valve for moving it out of said pocket and into the normal position.

15 14. A flushing device comprising a reservoir and a plunger section adapted to communicate with each other, a shiftable globular valve for closing communication between the two sections, said reservoir-section provided with a pocket adapted to receive said valve when shifted from normal position, a vertically - operable and gravity - return hollow plunger arranged in said plunger-section and adapted when operated to shift said valve into said pocket, and a vertically-movable means arranged in said reservoir-section and adapted to engage said valve for shifting it from said pocket into normal position.

20 15. A flushing device comprising a reservoir and a plunger section adapted to communicate with each other, a shiftable globular valve for closing communication between the

two sections, said reservoir-section provided with a pocket adapted to receive said valve when shifted from normal position, a vertically - operable and gravity - return hollow 55 plunger arranged in said plunger-section and adapted when operated to shift said valve into said pocket, and a float arranged in said reservoir-section and provided with means adapted to engage said valve for shifting it out of 60 said pocket into normal position.

16. A flushing device involving a reservoir-section communicating with a water-supply and provided with an outlet, a shiftable valve for closing said outlet, a float operable in said 65 reservoir-section and provided with a hinged deflecting-blade adapted to engage said valve when shifted for returning it to its closure position, combined with means for shifting said valve from its closure position. 7c

17. A flushing device involving a reservoir-section communicating with a water-supply and provided with an outlet, a shiftable means for closing said outlet, and a float of less diameter than said sections forming thereby a 75 water-passage, said float provided with means adapted to engage said valve when shifted for returning it to its closure position, and means carried by the float for increasing or decreasing the width of said passage, combined with 80 means for shifting said valve from its closure position.

18. A self-flushing device involving a water-chamber having an outlet, a valve for closing said outlet, a vertically-movable hollow 85 plunger for shifting said valve from its closure position, said plunger operable on the application of pressure and adapted to form a seal to prevent the discharge of water from said chamber until pressure is removed, and 90 a series of elements, one of which is connected with said plunger and adapted to be automatically operated when pressure is applied to impart a vertical movement to said plunger.

In testimony whereof I have hereunto set 95 my hand in presence of two subscribing witnesses.

OLIN M. ALEXANDER.
